(57) **CLAIM**

The ornamental design for a popcorn maker bowl, as shown
and described.

DESCRIPTION

FIG. 1 is a first perspective view of a popcorn maker bowl;
FIG. 2 is a second perspective view of the popcorn maker
bowl, illustrated in FIG. 1;

FIG. 3 is a top plan view of the popcorn maker bowl, illus-
trated in FIG. 1;

FIG. 4 is a bottom plan view of the popcorn maker bowl,
illustrated in FIG. 1;

FIG. 5 is a front elevational view of the popcorn maker bowl,
illustrated in FIG. 1;

FIG. 6 is a rear elevational view of the popcorn maker bowl,
illustrated in FIG. 1;

FIG. 7 is a left side elevational view of the popcorn maker
bowl, illustrated in FIG. 1;

FIG. 8 is a right side elevational view of the popcorn maker
bowl, illustrated in FIG. 1; and,

FIG. 9 is a cross-sectional view of the popcorn maker bowl
taken along line 9-9 of FIG. 3.

The characteristic features of the design reside in the non-
concentric container portion of the bowl and the distinct
curved portion on the outside flange of the bowl. The design-
ations of the views below as top, bottom, right side, front,
and rear are for ease of discussion only and are not intended
to limit the popcorn maker bowl to one particular orientation.
The popcorn maker bowl can be oriented in other directions
which would alter these designations. The drawings illus-
trated in FIGS. 1-9 are not necessarily drawn to the same
scale, and any change in scale between different views is not
intended to limit the popcorn maker bowl to a particular size.
